HYDRAULIC PUMP OR MOTOR

Horace E. McKibben, Grand Junction, and Benjamin I. Newton, South Haven, Mich., assignors to Hydro-Cam Drives Corporation, Grand Rapids, Mich.

Application March 31, 1948, Serial No. 18,158

14 Claims. (Cl. 103—136)

1

This invention relates to improvements in hydraulic pumps and motors.

The principal objects of this invention are:

First, to provide a hydraulic mechanism which can be used either as a pump or motor and which is particularly efficient and adapted for operation under high fluid pressures.

Second, to provide a hydraulic pump or motor of the rotary type in which the rotor is balanced relative to the casing and in which the vanes are positively moved into engagement with the periphery of the fluid chamber by rotation of the rotor.

Third, to provide a hydraulic pump or motor in which a plurality of rocket arms carried by the rotor are arranged to force the vanes of the rotor into operative position, receding motion of one vane acting through a rocker arm to extend another vane.

Fourth, to provide a hydraulic pump or motor having a rotor with lever actuated vanes so arranged that each vane is positively held in operating position during the entire working portion of its rotational cycle.

Fifth, to provide a rotor for a hydraulic pump or motor with pivotally mounted rocker arms for actuating the vanes of the rotor and to provide a support for said rocker arms which will automatically compensate for wear in the vanes or minor inaccuracies in the machining of the parts of the motor.

Other objects and advantages relating to the details of our invention will be apparent from a consideration of the following description and claims.

The drawings, of which there are two sheets, illustrate a preferred form of our pump or motor.

Fig. 1 is a cross sectional view taken along the plane of the line 1—1 in Fig. 2 and transversely of the axis of the pump or motor.

Fig. 2 is a cross sectional view taken along the plane of the line 2—2 in Fig. 1 and in the plane of the axis of the motor.

Fig. 3 is a fragmentary side elevational view of the body of the pump or motor partially broken away in cross section along the plane of the broken line 3—3 in Figs. 1 and 2 and illustrating the shape of the fluid passages in the motor block.

Fig. 4 is a fragmentary side elevational view of the motor partially broken away along the plane of the line 4—4 in Fig. 1 and with the rotor removed to illustrate the relative positions of the inlet and outlet ports at the rear of the block.

Our device is adapted to be used either as a

2

pump or as a motor depending upon whether energy is supplied to the device in the form of a prime mover connected to the shaft or in the form of fluid under pressure supplied to the working chambers of the device. For convenience in description the device will be referred to as a motor.

The motor consists of a generally cylindrical block 1 having parallel faces 2 and defining a central rotor chamber 3 open to both of the faces 2. The rotor chamber is closed by a front face plate 4 and a rear face plate 5 secured to the body by the cap screws 6.

The rotor chamber 3 is machined to provide opposed divider surfaces 7 and 8 which are located along a cylindrical surface centered at 9. On each side of the divider surfaces 7 and 8 the surface of the rotor chamber is extended from the center 9, as at 10, and merged with the opposite cylindrical surfaces 11 which are also centered on the center 9 but at a greater radius than the divider surfaces 7 and 8. The surfaces 11 form the working surfaces of the motor and the connecting surfaces 10 define the ports to the working chambers and will be described in detail presently.

The rotor chamber 3 rotatively receives the cylindrical rotor 12 which is accurately machined to fit snugly within the divider surfaces 7 and 8 and against the face plates 4 and 5. The rotor 12 is open on its rear side to the rear face plate 5 and is provided on its forward side with a disk-like body 13 connecting the periphery of the rotor to a hub 14. The hub 14 is received on the shaft 15 and keyed thereto, as at 16. The hub and shaft extend into the shaft housing 17 extending from the front side of the front face plate 4. Suitable bearings and packing (not illustrated) may be provided around the front end of the shaft and within the shaft housing 17.

The rear end of the shaft 15 is rotatably received in the roller bearing 18 mounted in a hole in the center of the rear face plate 5. A cover plate 19 secures the roller bearing in position.

The interior of the rotor 12 is provided with a series of five segmental arcuate recesses 20, which are illustrated in Fig. 1. Equally spaced between the arcuate recesses 20 the cylindrical portion of the rotor 12 defines five radial slots 21 slidably receiving the vanes 22. The base of each recess 20 defines a tapped aperture 23 (see Fig. 2) receiving the threaded end of a cap screw 24 having a smooth cylindrical shank 25 projecting into the recess 20. Rockably mounted on the shanks 25 are a series of rockers 26 having oppositely ex-

tending arms 27. The arms of each rocker are transversely offset so that the arms of adjacent rockers will overlap, as at 28, behind the inner ends of the vanes 22.

With particular attention to Fig. 1 it will be noted that as each vane 22 approaches one of the converging surfaces 10, that vane will be forced inwardly of the rotor and will bear against the arm of the rocker positioned ahead of that vane relative to the rotation of the rotor. The other arm of the rocker will press outwardly against the inner edge of the next preceding vane and force that vane outwardly along the diverging surface 10 following either of the divider surfaces 7 and 8. Each vane is therefore positively forced into working engagement with the working surfaces 11 of the fluid chamber.

It should further be noted that the working surfaces 11 are so proportioned angularly with respect to the divider surfaces 7 and 8 and the converging and diverging surfaces 10 that each vane is continuously held against the working surfaces 11 either by reason of the preceding vane and rocker arm being engaged by one of the divider surfaces or by the following vane and rocker being engaged by the other divider surface. It is thus impossible for fluid in the working chamber to work behind the edge of the vanes and drive them into the rotor regardless of how great the pressure of the fluid may be.

In order to compensate for wear in the edges of the vanes or for minor inaccuracies in forming the surfaces of the working chamber the rockers 26 are provided with slightly oblong or over-size holes, as indicated at 29, for reception of the screws 24. The inner surfaces of the rockers 26 are provided with centering bosses 30 and coil springs 31 are positioned around the bosses to urge the rockers outwardly against the screws 24. The inner ends of the springs 31 are secured around the centering bosses 32 on a ring 33 keyed to the shaft 15 so as to rotate with the rotor 12.

Attention is now directed to the manifolding or method of conducting the hydraulic fluid through the body of the motor to the rotor chamber 3. The block 1 of the motor is provided with a thickened boss 34 along one edge thereof which boss defines an inlet chamber 35 and an outlet chamber 36 opening to the face of the boss. The chambers 35 and 36 are suitably tapped or otherwise arranged to receive an inlet pipe 37 and an outlet pipe 38. Considering the motor as illustrated in Fig. 1, the top and bottom portions of the body 1 define annular fluid conducting by-pass chambers 39 opening directly to the inlet and outlet chambers. The inner walls 40 of these chambers form the working surfaces 11 of the upper and lower working chambers of the pump.

At the opposite edge of the motor block from the inlet chamber 35 and outlet chamber 36, the bypass chambers 39 merge into cross-over chambers 41 so that the upper by-pass chamber communicates with the inlet port 42 in the connecting surface 10 of the lower working chamber. The lower by-pass chamber 39 communicates through the upper cross-over chamber 41 with the outlet port 43 of the upper working chamber. The cross-over chambers in the block are formed by the use of suitable cores while casting the motor block so as to form a partitioned wall 44 which extends transversely to the axis of the shaft 15 between the ports 42 and 43 and twists in a spiral fashion to merge with the walls 40

which form the inner surfaces of the by-pass chambers.

It will thus be seen that fluid entering the inlet pipe 37 and chamber 35 will divide between the upper by-pass chamber and the upper working chamber. Fluid leaving the upper working chamber will pass through the lower by-pass chamber to the outlet chamber 36 while fluid from the upper by-pass chamber will be directed to the lower working chamber. By properly locating the leading edge of the upper partition wall 40 this division of the fluid can be made to be equal and the forces exerted by the fluid on the rotor or the rotor on the fluid will be balanced with respect to the axis of the rotor.

Particular attention is directed to Fig. 1 and the outlet ports 43, where it will be noted that the leading edge of the outlet port is cut back into the trailing edge of the working surface 11, as at 45, so that pressure on the vanes 22 will be relieved just prior to the engagement of the vane with the converging surface 10 of the block. The vanes and rockers are thus free to operate under the influence of the converging and diverging surfaces 10 without interference from the fluid pressure in the motor.

We have found that our motor will operate efficiently and without excessive friction when operated under high pressure and is, therefore, particularly well adapted for use as a fluid power conversion unit either as a pump or motor. We have described a highly practical commercial embodiment of our device so that others may reproduce the same with such minor modifications as are desired without further disclosure.

Having thus described our invention, what we claim as new and desire to secure by Letters Patent is:

1. A fluid operated power conversion device comprising, a block having parallel end faces and defining a rotor chamber open to said faces, opposed arcuate working faces in said chamber, opposed arcuate divider surfaces between said working faces and having shorter radii than said working faces, connecting surfaces between the ends of said working and divider faces, paired inlet and outlet ports formed in the connecting surfaces at the ends of each working face, fluid conducting chambers formed in said block outwardly of each of said working faces, said block defining an inlet chamber opening to one of said fluid conducting chambers and one of said inlet ports, said block defining an outlet chamber opening to the other of said fluid conducting chambers and one of said outlet ports, cross over chambers in said block at the opposite edge thereof from said inlet and outlet chambers and connecting said one fluid conducting chamber with the other of said inlet ports and connecting the other of said outlet ports with said other fluid conducting chamber, a hollow rotor having one open end and rotatable in said rotor chamber and against said divider faces, end plates for said block bearing against said rotor, a shaft for said rotor journaled in said end plates, five equally spaced recesses in the inner wall of said rotor, said rotor defining radial slots between said recesses, vanes slidably in said slots, rockers pivotally supported in said recesses and having oppositely extending rigidly connected arms engageable with the inner edges of the vanes on each side of each rocker, said rockers having a radially movable connection to said rotor at their pivots, and springs bearing between said rockers and said shaft to urge said rockers outwardly, said outlet

ports commencing in the rear edge of said working faces relative to the motion of said vanes whereby the pressure on each vane is relieved prior to the vane being retracted into the rotor by engagement with a connecting surface.

2. A fluid operated power conversion device comprising, a block having parallel end faces and defining a rotor chamber open to said faces, opposed arcuate working faces in said chamber, opposed arcuate divider surfaces between said working faces and having shorter radii than said working faces, connecting surfaces between the ends of said working and dividing faces, paired inlet and outlet ports formed in the connecting surfaces at the ends of each working face, fluid conducting chambers formed in said block outwardly of each of said working faces, said block defining an inlet chamber opening to one of said fluid conducting chambers and one of said inlet ports, said block defining an outlet chamber opening to the other of said fluid conducting chambers and one of said outlet ports, cross over chambers in said block at the opposite edge thereof from said inlet and outlet chambers and connecting said one fluid conducting chamber with the other of said inlet ports and connecting the other of said outlet ports with said other fluid conducting chamber, a hollow rotor rotatable in said rotor chamber and against said divider faces, end plates for said block bearing against said rotor, a shaft for said rotor journaled in said end plates, equally spaced recesses in the inner wall of said rotor, said rotor defining radial slots between said recesses, vanes slideable in said slots, rockers pivotally supported in said recesses and having oppositely extending rigidly connected arms engageable with the inner edges of the vanes on each side of each rocker, said rockers having a radially movable connection to said rotor at their pivots, and springs bearing between said rockers and said shaft to urge said rockers outwardly.

3. A fluid operated power conversion device comprising, a block having parallel end faces and defining a rotor chamber open to said faces, opposed arcuate working faces in said chamber, opposed arcuate divider surfaces between said working faces and having shorter radii than said working faces, connecting surfaces between the ends of said working and dividing faces, paired inlet and outlet ports formed in the connecting surfaces at the ends of each working face, fluid conducting chambers formed in said block outwardly of each of said working faces, said block defining an inlet chamber opening to one of said fluid conducting chambers and one of said inlet ports, said block defining an outlet chamber opening to the other of said fluid conducting chambers and one of said outlet ports, cross over chambers in said block at the opposite edge thereof from said inlet and outlet chambers and connecting said one fluid conducting chamber with the other of said inlet ports and connecting the other of said outlet ports with said other fluid conducting chamber, a hollow rotor rotatable in said rotor chamber and against said divider faces, end plates for said block bearing against said rotor, a shaft for said rotor journaled in said end plates, said rotor defining radial slots spaced therearound, vanes slideable in said slots, and rockers pivotally supported in said rotor in each space between said vanes and having oppositely extending rigidly connected arms engageable with the inner edges of the vanes on each side of each rocker.

4. In a fluid operated power conversion device

having balanced working chambers with inlet and outlet passages opening thereto, a rotor arranged to rotate between said chambers, divider surfaces engageable with said rotor between said working chambers, eccentric surfaces connecting the walls of said working chambers with said divider surfaces, said inlet and outlet passages opening through said eccentric surfaces, vanes radially slideable in said rotor and adapted to engage said divider surfaces and eccentric surfaces and the surfaces of said working chambers, rockers pivotally mounted within said rotor, one between each two adjacent vanes, oppositely extending rigidly connected arms on said rockers engageable with the inner edges of the vanes on each side of each rocker, the pivotal axes of said rockers being movable radially with respect to said rotor, and spring means urging said rockers radially outwardly of said rotor, the leading edges of said outlet passages being extended into the trailing edges of the walls of said working chambers relative to the rotation of said rotor.

5. In a fluid operated power conversion device having balanced working chambers with inlet and outlet passages opening thereto, a rotor arranged to rotate between said chambers, divider surfaces engageable with said rotor between said working chambers, eccentric surfaces connecting the walls of said working chambers with said divider surfaces, vanes radially slideable in said rotor and adapted to engage said divider surfaces and eccentric surfaces and the surfaces of said working chambers, rockers pivotally mounted within said rotor, one between each two adjacent vanes, oppositely extending rigidly connected arms on said rockers engageable with the inner edges of the vanes on each side of each rocker, the pivotal axes of said rockers being movable radially with respect to said rotor, and spring means urging said rockers radially outwardly of said rotor, said working chambers being so proportioned relative to said divider surfaces and said eccentric surfaces that each successive vane is continually held in extended position in said working chambers by reason of other vanes engaging said rockers and said divider surfaces.

6. In a fluid operated power conversion device having balanced working chambers with inlet and outlet passages opening thereto, a rotor arranged to rotate between said chambers, divider surfaces engageable with said rotor between said working chambers, eccentric surfaces connecting the walls of said working chambers with said divider surfaces, vanes radially slideable in said rotor and adapted to engage said divider surfaces and eccentric surfaces and the surfaces of said working chambers, rockers pivotally mounted within said rotor, one between each two adjacent vanes, and oppositely extending rigidly connected arms on said rockers engageable with the inner edges of the vanes on each side of each rocker, said working chambers being so proportioned relative to said divider surfaces and said eccentric surfaces that each successive vane is continually held in extended position in said working chambers by reason of other vanes engaging said rockers and said divider surfaces.

7. In a fluid operated power conversion device having balanced working chambers with inlet and outlet passages opening thereto, a rotor arranged to rotate between said chambers, divider surfaces engageable with said rotor between said working chambers, eccentric surfaces connecting the walls of said working chambers with said divider surfaces, vanes radially slideable in said rotor and

adapted to engage said divider surfaces and eccentric surfaces and the surfaces of said working chambers, rockers pivotally mounted within said rotor, one between each two adjacent vanes, oppositely extending rigidly connected arms on said rockers engageable with the inner edges of the vanes on each side of each rocker, the pivotal axes of said rockers being movable radially with respect to said rotor, and spring means urging said rockers radially outwardly of said rotor.

8. In a fluid operated power conversion device having balanced working chambers with inlet and outlet passages opening thereto, a rotor arranged to rotate between said chambers, divider surfaces engageable with said rotor between said working chambers, eccentric surfaces connecting the walls of said working chambers with said divider surfaces, vanes radially slideable in said rotor and adapted to engage said divider surfaces and eccentric surfaces and the surfaces of said working chambers, rockers pivotally mounted within said rotor, one between each two adjacent vanes, and oppositely extending rigidly connected arms on said rockers engageable with the inner edges of the vanes on each side of each rocker.

9. In combination with a fluid operated power conversion device including a block having balanced working chambers, a hollow rotor having one open end and being rotatable between said chambers, five equally spaced vanes carried by said rotor and movable successively through said chambers, segmental recesses in the inside of said rotor between each two adjacent vanes, a pin positioned in each recess and parallel to the axis of rotation of said rotor, rockers pivotally carried by said pins and each having rigidly connected oppositely extending arms engageable with the inner edges of the vanes adjacent to each rocker, said vanes and rockers being arranged relative to said rotor so that retraction of one vane will operate through one of said rockers to extend another vane, said rockers being radially movable relative to said pins, and springs urging said rockers outwardly relative to said pins, the arms on each rocker being offset longitudinally of said rotor whereby the meeting arms of adjacent rockers will overlap.

10. In combination with a fluid operated power conversion device including a block having balanced working chambers, a hollow rotor having one open end and being rotatable between said chambers, equally spaced vanes carried by said rotor and movable successively through said chambers, segmental recesses in the inside of said rotor between each two adjacent vanes, a pin positioned in each recess and parallel to the axis of rotation of said rotor, rockers pivotally carried by said pins and having rigidly connected oppositely extending arms engageable with the inner edges of the vanes adjacent to each rocker, said vanes and rockers being arranged relative to said rotor so that retraction of one vane will operate through one of said rockers to extend another vane, said rockers being radially movable relative to said pins, and springs urging said rockers outwardly relative to said pins.

11. In combination with a fluid operated power conversion device including a block having balanced working chambers, a rotor rotatable between said chambers, vanes carried by said rotor

and movable successively through said chambers, rockers pivotally carried by said rotor between each two adjacent vanes and having rigidly connected oppositely extending arms engageable with the inner edges of the vanes adjacent to each rocker, said vanes and rockers being arranged relative to said rotor so that retraction of one vane will operate through one of said rockers to extend another vane, said rockers being radially movable relative to said rotor, and springs urging said rockers outwardly.

12. In combination with a fluid operated power conversion device including a block having working chambers, a rotor rotatable between said chambers, vanes carried by said rotor and movable successively through said chambers, and rockers pivotally carried by said rotor between each two adjacent vanes and having rigidly connected oppositely extending arms engageable with the inner edges of the vanes adjacent to each rocker, said vanes and rockers being arranged relative to said rotor so that retraction of one vane will operate through one of said rockers to extend another vane.

13. In an apparatus of the character described, a block having inlet and outlet passages, a chambered rotor rotatably mounted in the block, the block having diametrically opposed cylinder lobes and diametrically opposed abutments coacting with the rotor to separate the lobes, a plurality of vanes radially reciprocable in said rotor, and rockers pivotally mounted within said rotor in each space between adjacent pairs of vanes, said rockers coacting with the vanes on each side thereof whereby each vane is constantly in driving engagement with a rocker.

14. In an apparatus of the character described, a block having inlet and outlet passages, a chambered rotor rotatably mounted in the block, the block having cylinder lobes and abutments coacting with the rotor to separate the lobes, a plurality of vanes radially reciprocable in said rotor, and rockers pivotally mounted within said rotor in each space between adjacent pairs of vanes, said rockers coacting with the vanes on each side thereof whereby each vane is constantly in driving engagement with a rocker.
